CLAIM

The ornamental design for a mixing base for multiple component cartridge or dispensing device, as shown and described.

DESCRIPTION

FIG. 1 is a top, rear-side perspective view of a mixing base for multiple component cartridge or dispensing device, showing my new design;

FIG. 2 is a bottom, rear-side perspective view thereof;

FIG. 3 is a bottom, front-side perspective view thereof;

FIG. 4 is a top plan view thereof;

FIG. 5 is a bottom plan view thereof;

FIG. 6 is a front view thereof;

FIG. 7 is a left side view thereof;

FIG. 8 is a rear view thereof; and,

FIG. 9 is a right side view thereof.
